UNITED STATES PATENT OFFICE

1,922,859

DYEING MACHINE

Joseph Portnoy, Philadelphia, Pa.

Application January 27, 1928. Serial No. 249,893

14 Claims. (Cl. 8—19)

In the dyeing and bleaching of any stock the following steps are always necessary:

1. Making up the dye-bath to the proper shade, or the bleaching bath to the proper strength;

5 2. Immersing the article to be dyed, or bleached therein;

3. Washing and finishing the article dyed or bleached.

10 It is obvious that if the article or material to be dyed were placed in the dye-bath before the same was properly made up to shade, it might result in

15 a. Improper shading, that is, the color to which the substance to be dyed would not be that which is desired, since the dye continues to go on the substance which is in the bath while the sample which is out of it is being compared by the dyer;

20 b. It might result in an improperly dyed batch, since the bath is bound to be deeper in shade at the point where the extra dye is first introduced. Fabrics near that point will, therefore, take on a deeper shade than those which are farthest away from the point of introduction. This difference will persist even after the dye has been 25 thoroughly mixed in the dye-bath.

It is also obvious that the longer any article remains in the dye-bath the more injurious it is to the fabric since the continued boiling and treatment tend to weaken the fibres.

30 In dyeing a batch of goods it often happens that it becomes dark before the batch is properly shaded. In such cases with the ordinary laundry machine type of dyeing machine now in general use, it is necessary to draw off the dye-liquor

35 when work is stopped and to make up a new dye-bath when work is begun again the next morning. Unless one goes to the trouble of taking the partially dyed articles out of the machine it becomes necessary to make up the dye-bath while 40 the articles to be dyed are in the machine. This may result in the spoiling of the entire batch being dyed, thereby necessitating a re-dyeing, and resulting in the weakening of the fabrics of the material being dyed.

45 Re-dyeing always necessitates a boiling operation. Boiling destroys the life and lustre of fabrics. This applies with especial force to the finer fabrics.

50 It is for the purpose of avoiding the difficulties and injurious results arising directly or indirectly from the fact that the material to be dyed is in the dye-bath while the dye-bath is being made up, or while the washing mixture, or the bleaching mixture, is being made up that the machine

for which Letters Patent are herein applied was invented and designed.

This machine, while it is intended to serve all dyeing needs, is of extra value to the dyer of fine and sheer fabrics. It has been designed not only for the purpose of obviating the injurious results 60 arising from re-dyeing, long boiling, etc., but also those arising from bulk dyeing.

The usual practice of dyeing fine and sheer articles, of which silk hosiery may be cited as an example, is to place a number of pairs of hose, say, two dozen, into a bag. A number of these bags are then thrown into the dyeing machine. If the dyeing machine is of the ordinary laundry type in common use, it has four sections. In such cases a comparatively large number of bags are 70 in one compartment. As the dyeing machine rotates, these bags rub against each other. The mass action of a number of such bags rubbing against any one of them produces a certain frictional force which is harmful to the life of the fabric. This is avoided in the present machine since each batch of two dozen is placed in its own compartment.

75 Bulk dyeing may also result in the imperfect assimilation of color by a lot of hose in a bag, or group of bags, which may become lodged in the middle of the batch in the dyeing machine, or in any section thereof. This is avoided by the use of the new multicell machine. The multicell arrangement makes it possible for the fabrics being processed to receive the greatest and most uniform contact with the processing fluids, chemicals or dyes.

80 Another object of this invention is to construct 90 a machine in which it will be possible to automatically remove the material to be dyed from the dye-bath whenever desired.

85 Another object of this invention is to construct 95 a machine in which it will be possible to dye in individual compartments individual units of a batch of articles.

Another object of this invention is to produce 100 a multicell dyeing machine whereby the actual frictional contact of bulk batches of articles to be dyed will be minimized.

These and other objects and advantages of the machine will become more obvious from the following specifications and the drawings there- 105 unto annexed.

In the drawings:

Figure 1 is a perspective view of the machine assembled, showing the multicell carrier raised 110 out of and above the dyeing vat, part of the front

of the dyeing vat being broken away, showing the secondary carrier therein.

Figure 2 is a side view of the multicell machine with the multicell in position inside the vat, parts 5 of the vat being broken away to show the assembly and part of the standard sheathing being removed to show the lifting gearing.

Figure 3 is a side view of the same side as Figure 2 with the multicell carrier raised above and out 10 of the dyeing vat, part of the side vat being cut out to show the secondary carrier therein.

Figure 4 is a top view of the locking device.

Figure 5 is a side view of the same.

Figure 6 is a front view of the same.

15 Figure 7 is a perspective view of the holder for the individual cells.

Figure 8 is a perspective view of one of the many individual cells.

Figure 9 is a fragmentary front view showing a 20 different type of standard which may be used to carry the individual cells and their holders.

Figure 10 is a top view of the multicell machine, with the multicell carrier locked in position within the vat. Parts of the vat and secondary carrier 25 are shown broken away.

Figure 11 is a section on the line 11-11 of Figure 10 showing the locking device for uniting the multicell carrier to the secondary carrier, the portions of the vat, secondary carrier and multicell carrier below the first row of compartments being broken away.

Figure 12 is a section on the line 12-12 of Figure 4.

Referring more specifically to the drawings, 35 reference numeral 1 designates a dyeing vat which may be of any size or shape, the preferred form being rectangular. Reference numeral 2 designates the secondary carrier. This carrier is rotatably mounted within the vat 1, one end being mounted in a suitable journal box and the other being directly and fixedly attached to a shaft 5, which is mounted in the side of the vat 1. The carrier is adapted for rotation both in a clockwise and counter clockwise direction. A 40 handle 4 is shown here as attached to the shaft 5. This is for the purpose of furnishing power to rotate the secondary carrier 2. For the handle may substituted a belt, one end of which is connected to the shaft 4 and another to a suitable source of power or a series of gears meshing with a gear 4-A mounted on shaft 4, the train being connected to a suitable source of power, or the shaft may be driven in any other way that is desired.

55 The secondary carrier 2 (see Figures 1, 2 and 3) is made up of a series of U shaped transverse braces 8, front and back braces 9 and side walls 10, the ensemble forming a wire basket. The walls 10 of the secondary carrier have portions 60 of the metal cut out, as shown at 11. This is for the double purpose of lightening the structure and for providing as much opening as possible through which the liquid in the dye-bath will flow and contact with the individual cells which 65 are carried by the secondary carrier. The side walls 10 are provided at their top with slots 12 which cooperate with the lugs 13 on the multicell carrier 3 to form a locking device which locks the multicell carrier within the secondary carrier.

70 The multicell carrier (see Figures 1, 2 and 3) is made up of series of transverse bars 14 joined to a series of upright bars 15, braced on the ends with the bars 16, the ensemble forming a series of shelves 17 which are divided by the upright bars 75 15 into a series of individual compartments 18.

One cell holder 19 (see Figure 7) is adapted to fit into each individual compartment 18. The back of the cell carrier 19 ends in a small upright wall 20, while the front end has a metal piece 21 bent downward. The wall 20 limits the motion of the individual cell 22 and serves to retain the same within the holder; the part 21 by contact with the bar 14 serves to limit the motion of the individual cell holder in the individual compartment.

80 The individual cell holders have a metal piece 22-A running the entire length on each side. Parallel to the part 22-A and below it there is a piece 23 which also runs the entire length of the carrier. The part 22 combines with the lower piece 23 to serve as a guide, runway and retaining element, the portions 22 and 23 cooperating with the lugs 24 on the individual cells 22 to retain the cells within the holders.

85 The individual cells 22 are boxes as shown, having removable covers and a plurality of perforations or openings therein. The openings are provided for the purpose of giving the dye-liquor an opportunity to come into contact with the material to be dyed.

90 Instead of combining a series of bars 14 with the uprights 15 to make the individual compartments 18 angles 25 may be mounted on the bars 15, as shown in Figure 9, the angles serving as runways for the individual cell holders.

95 The top of the multicell carrier has suitably mounted thereon two spaced guide members 26 (see Figures 1, 10 and 11). Fixedly attached to the outside of each of the guide members 26 is a spring 27 the other end of which is attached to an upright lug 13-A which forms the inside end of the lug 13. The lug 13 has slots 29 cut therein. Rivets 48 pass through the slots 29 and are securely fastened to the bar 14 of the multicell carrier. The head 48-A of the rivet 48 is wider than the slot 29. The rivet 48 combines with the slot 29 to form a means whereby the lug 13 is slidable along the top of the multicell carrier, the rivet 48 serving as a guide and retaining means for the lug 13. The springs 27, the lugs 13 and the slots 100 12, combine to form the mechanism which locks the multicell carrier to the secondary carrier.

105 Attached to the rear of the vat 1 or somewhere close thereto there is provided standards 7 in which is journaled a shaft 29, carrying gears 30 which mesh with a ratchet mechanism 31 slidably mounted in the standards 7. The shaft 29 ends in a handle 32 which serves as a source of power. Any other source of power desired may be substituted for the handle 32.

110 The ratchet mechanisms 31 have attached thereto crossheads 33. The crossheads 33 have attached thereto a plate 34, brackets 35 and a bracing plate 36.

115 The brackets 35 carry rollers which combine with the cam-shaped lugs 13-A to form a mechanism 135 which opens the locking device, serving to lock together the multicell carrier with the secondary carrier.

120 The plate 34 carries the mechanism which serves to cooperate with holes 37 in the guide members 26 on the multicell carrier 3 and lock the multicell carrier to the standards 33.

125 The locking device is made up of member 38 rotatably mounted on the plate 34 by means of a pin 39. The member 38 ends in a handle portion 40. The member 38 has two cam slots 41, in which pins 42 are movably mounted.

130 The pins 42 (see Figures 4, 6 and 12) are connected to bars or arms 43 which are slidably mounted under the bar 34 and held in position 135

by the guide pins 44, adapted to slide in slot 45 in the bar 34.

The bar or arm 43 ends in a wing 46 which carries two pins 47. These pins are adapted to mesh with holes 37—A in standards 33 and holes 5 37 in the guides 26.

The operation of the device is as follows:

We start with the vat 1 empty and the carrier 3 in the upright position shown in Figure 1.

Water is fed into the vat 1 by means of pipe A. 10 This may be heated to any temperature desired by introducing steam through pipe B. The liquor in the vat is now prepared for the purpose needed by adding the necessary softeners, dye in the amount required, etc. The entire mass is 15 thoroughly agitated by operating the secondary carrier 2, which thus serves as a mixer during this operation.

In the meantime, the stock to be dyed has been prepared. Each small batch has been put in 20 cotton nets and these into the individual cells 22 or each batch has been put directly into the individual cells. The cells have been mounted in the individual carriers 19. These are now loaded into the multicell carrier 3. If the multicell carrier 25 is too high it may always be lowered to the height desired by operating the raising and lowering mechanism 7, 31, 32 and associated parts. When the individual carriers desired have all been mounted in the multicell carrier, the multicell carrier is lowered into the vat by operating the 30 handle 32 in the proper direction. This actuates the ratchet mechanism 31 through contact with the gear 30. A suitable pawl is provided to lock the mechanism in place.

The multicell carrier assumes the position within the secondary carrier 2 shown in Figure 2. Moving the handle 40 of the locking device 38 in a counter-clockwise direction serves to pull the pins 47 out of the holes 37 and 37—A thereby releasing the standard 33 and associated mechanism from the auxiliary carrier.

The handle 32 is now operated in the proper direction this raising the standards 33 and the plate 34.

45 As the plate 34 is raised the rollers 49 slide along the cam surfaces of the lug 13—A. While this is occurring the spring 27 exerts pressure on the reverse side of the cam surfaces 13—A, thus pushing the slides 13 into the slots 12. This serves to lock the multicell carrier to the secondary carrier. Power is now applied to the shaft 5 and the secondary carrier with its burden is rotated 50 for the period desired and until the fabric has assumed the proper shade. It is then stopped and the lifting mechanism 33 is lowered by a proper manipulation of the handle 32.

The steps previously described are now reversed as the plate 34 descends the surfaces of the rollers 49 first come in contact with the cam surfaces of the slides 13—A. On further descent of the standards 33 the rollers 49 sliding along the cam surfaces 13—A exert a pressure which tends to pull in the slides 13 and pull them out of the slots 12, thus unlocking the multicell carrier from 60 the secondary carrier. When the multicell carrier reaches the position shown in Figure 2, the handle 40 is now pushed in clockwise direction which exerts a pressure on the pins 47 forcing them into the holes 37 and 37—A, thus locking the lifting device to the multicell carrier. The handle 32 of the lifting device is operated in a proper direction, this lifting the entire multicell carrier out of the dye vat.

The dye-liquid is now run out of the vat 1. 75 Water for cleaning purposes is run in and

warmed to the proper temperature. The multicell carrier is immersed and more water is sent through the vat until the stock has been properly cleaned.

The multicell carrier is now again lifted out of the vat and unloaded.

If night should happen to fall while a batch is being dyed all that is necessary with the machine herein described is to lift the multicell carrier out of the vat 1, let it remain that way 80 over-night, leave the dye-liquid in the vat, and start the next morning where work was left the night before by merely lowering the stock into the dye-mixture. A quadruple advantage is thus obtained:

- a. Saving of dye mixture,
- b. Assuring oneself of the proper shades, and
- c. The saving of time; and
- d. The obviation of any possibility or necessity of redyeing and the concomitant boiling treatment so injurious to the life of the fabric.

90 By means of this machine it is also possible to warm the rinsing water by means of steam without inserting the material to be dyed in the water before the water has been raised to the proper temperature. This is of particular advantage in dye-houses using the ordinary washing machine type of dyeing machine but which does not have a hot water line.

In such cases cold water is first run into the 100 machine. This congeals the free and loosened gum which may have remained over in the liquid causing pasty pellets and other impurities to stick to the material to be dyed, thus smearing the fabric.

110 The only way to remove these spots is to boil the stock again in soap or some other solution to wash away the impurities. This continued boiling destroys the life and lustre of the fibre.

115 Where sheer fabrics such as silk textures and silk hosiery are being dyed, dyeing by this particular machine and process will not only reduce the amount of damage and of waste, but will also increase the life of the garment or article dyed.

120 The above disclosure is by the way of illustration only and not by the way of limitation since many changes may be made in the specific structure of any element or group of elements without departing from the spirit of my invention. For instance, the shape of the vat 1 may be changed, this would in turn affect the shapes of elements 2 and 3. Or, the secondary carrier may be entirely eliminated, suitable locking devices being in such a case provided to keep the individual cells and their holders locked in the multicell carrier. Or, the holders for the individual cells may be eliminated; or the locking mechanism may be changed; or the lifting mechanism may be changed; or any combination of these elements 125 may be changed without changing the device 130 in principle and operation.

135 Having described my invention, what I claim as new and useful is:

1. A dyeing machine consisting of a vat, a carrier rotatably mounted in said vat, a multicell carrier mounted for movement into and out of operative relation with the said first carrier, a holder removably carried by the said multicell carrier and individual containers carried by the said holder, the said individual containers adapted to hold the material to be dyed.

140 2. A dyeing machine consisting of a vat, a carrier rotatably mounted in said vat, a multicell carrier mounted for movement into and out of 145 operative relationship with the said first carrier,

- a locking device carried by the said multicell carrier and a lifting means for the said multicell carrier mounted in operative relationship to the said multicell carrier, the said lifting means consisting of a standard, a rack carried by the said standard, a shaft carried by the said standard, a gear carried by the said shaft, the said gear meshing with the said rack, an arm carried by the said rack, a locking device carried by the said arm, the said locking device cooperating with the said locking device on the said multicell carrier to lock the multicell carrier to the lifting means.
3. A dyeing machine consisting of a vat, a carrier rotatably mounted in said vat, openings in the ends of said carrier, a multicell carrier movable into and out of operative relationship with the said carrier, locking means carried by the said multicell carrier, the said locking means consisting of a lug, a spring attached to the said lug, secondary locking means carried by the said multicell carrier, the said secondary locking means consisting of a bar and openings in said bar, means for lifting and lowering the said multicell carrier into and out of operative relationship with the said first carrier, the said lifting means consisting of standards, a rack carried by each of said standards, a shaft carried by the said standards, gears carried by the said shaft, the said gears operatively connected with the said racks whereby the racks may be raised and lowered, an arm carried by each of said racks, locking means carried by each of the said arms the said locking means consisting of a bracket and a roller carried by the said bracket, the said locking means placed in operative relationship with the said first locking means on the multicell carrier and cooperating with the said first locking means on the said multicell carrier to lock and unlock the said multicell carrier to the said first carrier, a second set of locking means carried by the said arms, the said locking means consisting of a plate, means for actuating said plate, cam slots on said plate, pins movably mounted within the said cam slots, arms operatively connected to the said pins, the said second set of locking means cooperating with the said second set of locking means on the said multicell carrier to lock the said arms to the said multicell carrier.
4. In a dyeing machine consisting of a vat, a carrier rotatably mounted in said vat, a multicell carrier mounted for movement into and out of operative relation with the said first carrier and lifting means for lifting and lowering the said multicell carrier means for locking the said multicell carrier to the said lifting means, the said locking means consisting of a male member and female member, the said male member consisting of a plate, means for actuating said plate, a cam slot in said plate, means movably mounted within said cam slot, and an arm operatively connected to said means, the said female member consisting of a bar and a slot in said bar, the said slot adapted to receive the said arm on the said male member.
5. In a dyeing machine consisting of a vat, a carrier rotatably mounted in said vat, a multicell carrier mounted for movement into and out of operative relation with the said first carrier and lifting means for lifting and lowering the said multicell carrier means for locking the said multicell carrier to the said lifting means, the said locking means consisting of a male member and a female member, one carried by the said lifting means and the other carried by the said multicell carrier, the said male member consisting of a plate, means for actuating said plate, cam slots in the said plate, pins movably mounted within said cam slots and cams operatively connected to the said pins, the said female member consisting of bars, and a slot in each of said bars, the said slot adapted to receive the said arms on said male members.
6. A locking device consisting of a male member, a female member and a third member, the said male member consisting of a lug operatively positioned to enter a cooperating slot formed in said female member a cam surface on said lug and a spring attached to said lug; the said female member consisting of a bar having a slot formed therein for receiving the said lug carried by the said male member, the said third member consisting of an arm, the said arm adapted to contact with said cam surface and actuate the said lug, means for raising and lowering the said arm into and out of operative relationship with the said cam surface whereby the lug will move out of and into the said slot.
7. A locking device consisting of a male member, a female member and a third member mounted for vertical movement with respect to the male member; the said male member consisting of a lug operatively positioned to enter a cooperating slot formed in the said female member, a cam surface carried by the said lug and a spring attached to the said lug for imparting positive movement to the said lug, the said female member consisting of a bar having a slot formed therein for receiving the said lug; the said third member consisting of an arm mounted for vertical movement with respect to the said lug, the said arm adapted to contact with the said cam surface and actuate the said lug in a direction opposite to that in which the said lug is actuated by the said spring.
8. A locking device consisting of a male member, a female member and a third member mounted for vertical movement with respect to the male member; the said male member consisting of a plurality of lugs operatively positioned to enter cooperating slots formed in the said female member, a cam surface carried by each said lug and a spring operatively attached to each said lug for imparting positive movement to each said lug; the said female member consisting of a plurality of bars having slots formed therein for receiving the said lugs; the said third member consisting of a plurality of arms mounted for vertical movement with respect to the said lugs, each said arm adapted to contact with a cam surface on one of said lugs and actuate the said lug in a direction opposite to that in which said lug is actuated by said spring.
9. A locking device consisting of a male member, a female member and a third member mounted for vertical movement with respect to the male member; the said male member consisting of a lug operatively positioned to enter a cooperating slot formed in the said female member, one of the ends of the said lug terminating in a bar substantially at right angles to the lug, a cam surface formed on the said bar and a spring attached to the said bar for imparting positive movement to the said lug; the said female member consisting of a bar having a slot formed therein for receiving the said lug; the said third member consisting of an arm mounted for vertical movement with respect to the said bar, the said arm adapted to contact with the said cam surface and actuate the said

lug in a direction opposite to which the said lug is actuated by the said spring.

10. A locking device consisting of a male member, a female member and a third member mounted for vertical movement with respect to the male member; the said male member consisting of a plurality of lugs operatively positioned to enter cooperating slots formed in the said female member, one of the ends of each of the said lugs terminating in a bar substantially at right angles to the said lug, a cam surface formed on each said bar and a spring attached to each said bar for imparting positive movement to each said lug; the said female member consisting of a plurality of bars having slots formed for receiving the said lugs; the said third member consisting of a plurality of arms mounted for vertical movement with respect to the said bar, each said arm adapted to contact with each said cam surface and actuate the said lug in a direction opposite to that in which the said lug is actuated by the said spring.

11. A dyeing machine consisting of a vat; a carrier rotatably mounted in said vat; a multicell carrier mounted for movement into and out of operative relationship with the first said carrier; lifting means for the said multicell carrier mounted in operative relationship with the said multicell carrier; and a locking member for locking the said multicell carrier to the said lifting means,—a portion of the said locking member being carried by the said multicell carrier and a cooperating portion of the said locking member being carried by the said lifting member.

12. A dyeing machine consisting of a vat; a carrier rotatably mounted in said vat; a multicell carrier mounted for movement into and out of operative relationship with the first said carrier; lifting means for the said multicell carrier—the said lifting means consisting of standards, a rack carried by each of said standards, a shaft carried by the said standards, gears operatively connected with the said rack carried by the said shaft for raising and lowering the said racks, and an arm carried by each rack; and locking means for locking the said multicell carrier to

the said lifting means,—a portion of the said locking means being carried by the said multicell carrier and the cooperating portion of the said locking means carried by said arms.

13. A dyeing machine consisting of a vat; a carrier rotatably mounted in the said vat; a multicell carrier mounted for movement into and

80

out of operative relationship with the first said carrier; locking means for locking the said multicell carrier to the first said carrier,—a portion of the said locking means being formed on the first said carrier and the cooperating portion of the said locking means being formed on the said multicell carrier; lifting means for lifting and lowering the said multicell carrier into and out of operative relationship with the first said carrier—the said lifting means consisting of standards, a rack carried by each of said standards, a shaft adapted to be connected to a source of power carried by the said standards, gears operatively connected with the said rack carried by the said shaft whereby the rack may be raised and lowered and an arm carried by each rack; and locking means for locking the said multicell carrier to the said lifting means,—a portion of 90

85

the said locking means being carried by the said multicell carrier and the cooperating portion of the said locking means being carried by the said

95

locking means carried by the said arms.

14. A dyeing machine consisting of a vat; a carrier rotatably mounted in the said vat; a multicell carrier mounted for movement into and out of operative relationship with the first said carrier; locking means for locking the said multicell carrier to the first said carrier,—a portion of 100

105

the said locking means being carried by the said multicell carrier and the cooperating portion of the said locking means being carried by the said

110

locking means carried by the said arms.

15. A dyeing machine consisting of a vat; a carrier rotatably mounted in the said vat; a multicell carrier mounted for movement into and

115

out of operative relationship with the first said carrier; locking means for locking the said multicell carrier to the first said carrier,—a portion of 120
